BOTTLE

William L. Lee, Phoenix, Md., and James A. Shepler, Toledo, Ohio, assignors to Owens-Illinois, Inc., a corporation of Ohio

Filed Sept. 22, 1965, Ser. No. 87,106

Term of patent 14 years

(Cl. D58—6)

FIG. 1

The back and sides not shown are the same as the front shown. The characteristic features of this design reside in the configuration shown in full lines on the drawing.

We claim:

The ornamental design for a bottle, substantially as shown and described.
